UNITED STATES PATENT OFFICE.

WILLIAM P. BETTENDORF, OF DAVENPORT, IOWA.

DESIGN FOR A CENTER SILL FOR CARS.

SPECIFICATION forming part of Design No. 30,635, dated April 25, 1899.

Application filed March 30, 1899. Serial No. 711,161. Term of patent 14 years.

To all whom it may concern:

Be it known that I, WILLIAM P. BETTENDORF, a citizen of the United States, and a resident of Davenport, in the county of Scott and State of Iowa, have invented and produced a new and original Design for Center Sills for Cars, of which the following is a specification.

The drawing shows a perspective view of my invention.

10 As shown in the drawing, the leading or material part of my invention is the curvature of the lower edge of the center sill.

15 In the drawing, A represents a beam having its longitudinal edges flanged, its upper edge a straight, and its lower edge b curved in such manner as to make the height of it different at different points along its length.

Thus for a given distance from each end of the beam its longitudinal edges are parallel.

20 Then the upward curvature of said lower edge

b decreases the distance between its flanges to such an extent that at the point c, where the said sill when in use passes over the body-bolsters of a car, it attains its minimum height. Between these points c the lower edge inclines 25 downward and converges toward the central portion about the center of length of the beam, where it attains its maximum height, and thus gives said center sill a truss shape between the points where its height is the least. 30

Having described my invention, what I claim as new, and desire to secure by Letters Patent, is—

The design for the center sill of a car, as herein shown and described.

WILLIAM P. BETTENDORF.
